[57] CLAIM

The ornamental design for a multi-purpose tool for can pull-tabs, slide fasteners or the like, as shown and described.

DESCRIPTION

FIG. 1 is a front elevational view of a multi-purpose tool for can pull-tabs, slide fasteners, or the like showing my new design;

FIG. 2 is a rear elevational view thereof;

FIG. 3 is a left side elevational view taken from FIG. 1;

FIG. 4 is a left side elevational view taken from FIG. 2;

FIG. 5 is a bottom plan view taken from FIG. 1; and

FIG. 6 is a top plan view taken from FIG. 2.

FIG. 1

FIG. 2

FIG. 3

FIG. 4

FIG. 5

FIG. 6
